UNITED STATES PATENT OFFICE.

ANTHONY C. MILLER AND CORA L. MILLER, OF BATTLE CREEK TOWNSHIP, CALHOUN COUNTY, MICHIGAN.

PLATE-LIFTER.

No. 894,894.

Specification of Letters Patent.

Patented Aug. 4, 1908.

Application filed March 8, 1907. Serial No. 361,284.

To all whom it may concern:

Be it known that we, ANTHONY C. MILLER and CORA L. MILLER, citizens of the United States, residing at the township of Battle Creek, county of Calhoun, and State of Michigan, have invented certain new and useful Improvements in Plate-Lifters, of which the following is a specification.

This invention relates to improvements in 10 plate lifters.

The main object of this invention is to provide an improved plate lifter which is convenient to use, attractive in appearance and, at the same time, is strong and durable, and 15 one which is comparatively economical to produce.

Further objects, and objects relating to details of construction, will definitely appear from the detailed description to follow.

20 We accomplish the objects of our invention by the devices and means described in the following specification.

The invention is clearly defined and pointed out in the claims.

25 A structure embodying the features of our invention is clearly illustrated in the accompanying drawing, forming a part of this specification, in which,

Figure 1 is a plan of our improved plate 30 lifter with the arms shown in their extended position. Fig. 2 is an enlarged detail cross section thereof, taken on a line corresponding to line 2—2 of Fig. 1, showing details of construction. Fig. 3 is an enlarged longitudinal section taken on a line corresponding to line 3—3 of Fig. 2. Fig. 4 is an enlarged detail taken on a line corresponding to line 35 4—4 of Fig. 1, showing the manner of grasping a plate or dish.

40 In the drawing, the sectional views are taken looking in the direction of the little arrows at the ends of the section lines, and similar reference characters refer to similar parts throughout the several views.

45 Referring to the drawing, the rod-like handle 1 is provided with a grip or hand piece 2, the rod 1 preferably being of iron and the grip or hand piece of wood. The arms 3 and 3' are formed of single pieces of 50 wire bent to form plate engaging hooks 10 at their outer ends. The ends of the arms 3 are inserted and rigidly secured in the collars 4 which are secured to the handle 1 by suitable keys 11. The ends of the arms 3' are 55 secured to the sleeve 5 which is revolvably

mounted upon the rod and held in place thereon by the collars 4 which are adapted to embrace the ends thereof, as clearly appears in Fig. 3. The sleeve 5 is preferably provided with a bushing 6, the bushing being 60 formed of hard fiber or wood or the like. It is evident that it could, if desired, be formed of one piece. By this arrangement, the arm 3' is secured to the handle to rock thereon. To limit the upward movement of the arms 65 3' we provide one of the collars 4 with an inwardly-projecting stop adapted to engage the arms, see Fig. 1. The ends of the arms are preferably secured to the collars by inserting into suitable holes provided therefor 70 and upsetting or punching the metal into the notches 12 formed for the purpose in the ends of the wire.

The ends of the wire forming the arm 3' we preferably secure by notching the same 75 and arranging the screw pins 14 to engage these notches. This forms a simple and at the same time a very effective securing means.

The arms 3 and 3' are, as stated, formed of 80 a single piece of wire, the ends being looped back upon themselves and turned into downturned hooks 10, the ends of the loops forming cross pieces 15 which are arranged in a plane with the side wires of the arms so as 85 not to interfere with the grasping of a dish by the hooks.

The cross pieces 15 are preferably turned into spring loops 16, thereby, in effect, providing a spring connection for the hooks 10. 90 This insures their effective grasping of the plate.

In use, the swinging or pivoted arm is first engaged over one edge of the plate and then the fixed arm. An upward lift on the handle, with a rocking movement of the same toward the fixed arm to swing it onto the plate, will effectively engage the hook, so that the plate can be lifted without danger of dropping the same.

95 Our improved plate lifter is specially designed for use in removing articles from an oven, such as pies, and the like, although it will be found adapted for use in a very great variety of relations.

100 Having thus described our invention, what we claim as new and desire to secure by Letters Patent is:

1. In a plate lifter, the combination of the 110 rod-like handle; a pair of loop-like arms

formed of wire, each having downturned spaced hooks at their outer ends; collars to which the ends of the wire forming one of said arms are secured, keyed to said handle whereby the arm is rigidly connected therewith; a sleeve to which the ends of the wire forming the other arm are secured revolubly mounted on said handle between said collars; and a stop extension on one of said collars adapted to limit the upward movement of the swinging arm, as specified.

2. In a plate lifter, the combination of the rod-like handle; a pair of loop-like arms formed of wire, each having downturned spaced hooks at their outer ends; collars to which the ends of the wire forming one of said arms are secured, keyed to said handle whereby the arm is rigidly connected therewith; and a sleeve to which the ends of the wire forming the other arm are secured revolubly mounted on said handle between said collars, said collars being adapted to receive the ends of said sleeve; and a stop extension on one of said collars adapted to limit the upward movement of the swinging arm, as specified.

3. In a plate lifter, the combination of the rod-like handle; a pair of loop-like arms formed of wire; collars to which the ends of

the wire forming one of said arms are secured, keyed to said handle whereby the arm is rigidly connected therewith; a sleeve to which the ends of the wire forming the other arm are secured revolubly mounted on said handle between said collars; and a stop extension on one of said collars adapted to limit the upward movement of the swinging arm, as specified.

4. In a plate lifter, the combination of the rod-like handle; a pair of loop-like arms formed of wire; collars to which the ends of the wire forming one of said arms are secured, keyed to said handle whereby the arm is rigidly connected therewith; and a sleeve to which the ends of the wire forming the other arm are secured revolubly mounted on said handle between said collars, as specified.

In witness whereof, we have hereunto set our hands and seals in the presence of two witnesses.

ANTHONY C. MILLER. [L. S.]
CORA L. MILLER. [L. S.]
